CORSAGE PIN

Leonard M. Dorman, Meadville, Pa., assignor to
Talon, Inc., a corporation of Pennsylvania

Application June 5, 1953, Serial No. 25,349

Term of patent 3½ years

(Cl. D45—19)

To all whom it may concern:

Be it known that I, Leonard M. Dorman, a citizen of the United States, residing at Meadville, in the county of Crawford and State of Pennsylvania, have invented a new, original, and ornamental Design for a Corsage Pin, of which the following is a specification, reference being had to the accompanying drawing, forming a part thereof.

In the drawing:

Fig. 1 is a front elevational view of the corsage pin, showing my new design, as it appears in its open position;

Fig. 2 is a side elevational view of the pin, as shown in Fig. 1;

Fig. 3 is a rear elevational view, the same as shown in Fig. 1;

Fig. 4 is a front elevational view of the pin of my new design, as it appears in its closed position; and

Fig. 5 is an end elevational view of the pin, as shown in Fig. 1.

I claim:

The ornamental design for a corsage pin, substantially as shown and described.
